UNITED STATES PATENT OFFICE

2,418,014

WINDOW CONSTRUCTION

Elmer L. Daab, University City, Mo.

Application June 2, 1944, Serial No. 538,442

1 Claim. (Cl. 189—72)

1

This invention relates to windows, and with regard to certain more specific features, to double-hung, counterbalanced windows.

Among the several objects of the invention may be noted the provision of a reliable low-cost, double-hung window of the counterbalanced variety which is simple in design, installation and operation; the provision of a counterbalanced window of the class described which may be operated with or without counterbalancing; and the provision of a window of this class which in use presents a good appearance. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawings, in which is illustrated one of various possible embodiments of the invention,

Fig. 1 is a vertical section of the new window;

Fig. 2 is an enlarged horizontal section taken on line 2—2 of Fig. 1;

Fig. 3 is a vertical detailed section taken on line 3—3 of Fig. 1;

Fig. 4 is a vertical detailed section taken on line 4—4 of Fig. 1;

Fig. 5 is a diagrammatic vertical section illustrating counterbalancing operation; and,

Fig. 6 is a view similar to Fig. 5 illustrating alternative unbalanced operation.

Similar reference characters indicate corresponding parts throughout the several views of the drawings.

The drawings show one side of a symmetrical window and where parts are duplicated, only one is shown, in order to avoid superfluity.

Referring now more particularly to Figs. 1 and 2, numeral 1 generally indicates a hollow metal window frame composed of vertical side jambs 3 in which are grooved sections 5 and 7. The vertical jambs 3 are connected by a horizontal head jamb 9 and by a horizontal bottom sill 11. The outside of the head jamb 9 is extended downward as a weather head 13.

Within the head jamb 9 is a channel 15 held by flanges 16. On each side of the frame, within the channel 15 is an L-shaped bracket 17 carrying pins 19 for sheaves 21. On each bracket 17 is a cover 23, held to the bracket 17 by the same pins that support the sheaves. Thus the entire sheave assembly is nested within the gen-

2

erally U-shaped construction of the head jamb so that there are no undesirable protuberances from the rectangular outline of the frame. Thus in installing the frame in a rectangular wall opening no local parts of the wall need to be knocked out. The entire construction presents a rectangular outline which fits within the ordinary rectangular window recess left within a wall.

10 Within the outer vertical recesses 5 slides an outer upper metal window sash 25, carrying a window pane 27 and having a lower meeting rail 29. In the other or inner recesses 7 slides an inner lower metal window sash 29, carrying a pane 31 and having an upper meeting rail 33. The rails 29 and 31 meet at weatherstrip 35 when the sashes are closed.

The upper sash is spaced inward from the depending weather head 13 so that if this upper sash is lowered a short distance, without its top emerging from the head, limited circulation of air may occur between the window and the weather head without entry of rain or the like. This fact will again be referred to in connection with another element of the invention.

Bolted to the opposite ends of the head member of the inner sash 29 are U-shaped pieces 35, each comprising a horizontal extension member and a bumper head extending upward therefrom within the respective groove 7 in the side jamb for cooperation with bumpers 37 carried on the head jamb. This cooperation occurs when the inner sash rises to the upper end of its travel.

Each vertical edge of each window is formed with flanges 39 which extend into the grooved portions 5 and 7, respectively (Fig. 2). These flanges 39 are grooved as indicated at 41 and carry spring weatherstrip members 43 which operate with the frame recesses 5 and 7.

40 The flanges 39 determine channel-shaped spaces 45 on each side of each sash. Each space 45 in the lower sash is used as a channel for a sliding weight 47 composed of a lead element 43 carried by a bail 49. Into the head of the bail is 45 screwed a thimble 51 through which is a hole for accommodating a stainless steel cord 53. One end of the cord is provided with a holding head 50 below the hole. The upper end of the thimble 51 is slotted as shown at 55 so that by means of 50 a spanner tool, the thimble may be adjusted up and down in the bail 49. This determines the position of the weight 47 in the channel 45 with the top of the bail just under member 35. Each member 35 is provided with a circular opening 54 which accommodates the upper end of the thimble

51 but does not accommodate the upper flat portion 52 of the bail 49. Thus when the bail is adjusted with the flat portion 52 just under the opening 54, the lower inside sash may be supported by the bail and act as a counterweight for the outer window in all positions of both. It is to be understood that the weight in the parts 48 and 49 forming the sliding weight element 47, is not enough in itself to counterbalance the outer window but only enough to maintain suitable tension in the respective cord 53, for reasons which will appear.

Each cord 53 passes up through an opening 57 in the head jamb 9 and channel 15, thence over the sheaves 21 and down through other openings 59 through said channel 15 and head jamb 9. The second reach of the cord 53 passes down to a second thimble 61 where it is provided with a holding head or knots 64 below the thimble 61. This thimble 61 is threaded into a fixed block 62 in the upper portion of the outer sash 25. The cord may move down through the thimble should it become necessary that it so move. As will appear, this requires that the inner sash be raised. This movement allows for tying the knot 64 and also take-up of any excess cord.

The connection produced by this second thimble 61 with the upper portion of the outer window 25 is fixed since block 62 is fixed (see Fig. 3). On the other hand, each thimble 51 is connected only to a weighted bail 49 (Fig. 4). It is on the bails 49 that the lower sash is supported. But the inner sash may be raised with respect to the weighted bails independently of counterweighting by the outer sash, provided the outer sash is not allowed to descend. Under such circumstances each weighted bail 49 slides relatively down its respective space 45 in the lower sash as the lower sash rises. This may be referred to as a lost-motion connection between the weighted bails and the lower sash.

In order to prevent the upper sash from descending, whenever this is desired it is provided with oppositely located, lower latch bolts 65. These cooperate with suitably located openings 67 in the jamb 3. Each opening 67 on each side of the jamb is at such an elevation that when the respective latch bolt 65 engages therewith, the upper sash 25 is held up in closed position.

The lower sash is provided at its bottom sides with opposite latches 69 of the general type used on railway windows and the like. The bolts 71 of these latches cooperate with openings 73 in the vertical jambs 3. The cooperation is selective so that the inside sash may be locked down in its shut position, or locked in various elevated positions.

Operation is as follows:

Alternative I:—Latch bolts 65 of the upper sash may be released, in which event the weight of the outside sash 25 is applied to the cords 53 to counterbalance the inner sash. This is because of the engagement of the flat portions 52 of the bails 49 underneath the members 35. Hence when the latches 69 on the lower sash are released, the lower sash may be opened with counterbalancing by the outer sash. The outer sash at this time lowers.

In addition, if the latches 69 are engaged in any set of openings 73, both windows will be locked against further opening. The second set of openings 73 are at an elevation such that the upper edge of the outer sash 25 becomes located in the neighborhood of the lower edge of the weather head 13, but not cut from under it. This allows

6 ventilation under the weather head 13 and over the outer sash without admitting rain or the like (Fig. 5).

The lower sash may also be raised to its other positions, including its upper limit wherein the member 35 engages the bumper 37. At this time the outer sash descends to its lower limit, functioning during the action of opening the window as a counterbalance for the inner sash.

Fig. 5 shows the opening operation under counterbalanced condition wherein the lower sash has been unlocked and raised to bring the upper sash down without having the upper edge of the latter pass the lower edge of said weather head 13. Under these conditions the windows are locked at 69. Both windows may of course be opened further than shown in Fig. 5 under the counterbalance conditions.

Alternative II:—If it is desired to have the window operate without counterbalancing, then before the opening operation is started, the latch bolts 65 of the upper sash are thrown into the openings 67 prior to lifting the lower sash. Then when the lower latches 69 on the inner sash are released and this inner sash lifted (see Fig. 6), then there is no counterbalancing action on the inner sash by the outer sash. This is because the weight assemblies 47 remain stationary in spaces 45 as the inner sash lifts. This stationary condition is indicated by the dotted lines in Fig. 6. The inner sash is then held open by reclosing the latches 69 in connection with desired sets of the openings 73. The lost-motion action of the weights 47 in the spaces 45 when the inner sash is lifted without counterbalancing, avoids snagging and looping of the cord 53.

Closing of the window under either alternative I or II is done simply by pushing down the inner sash and allowing the latch 69 to catch in the lowermost opening 73.

It may be observed that the operator under the alternative II lifts the weight of the inner sash. If the inner sash is large and heavy, it may be desired to use one of the available window lifters now on the market for aid in lifting the unbalanced sash.

In view of the above, it will be seen that the invention has the advantage of the stated alternative counterbalanced or unbalanced operation, the latter allowing the upper sash to remain closed. Its construction is simple and it is easy to operate.

Furthermore, there are no projections beyond the limit of the window frame so that there is no interference with easy erection within the openings usually prepared in a building for the purpose. Neither are there engineering problems in head construction such as are incidental to most other types of windows of this class. All operating mechanism is within the frame and may be installed in the factory. It will be noted in this connection that the weights 47 operate within a space in the sash, and not within any space within the wall that needs to be prepared for it, other than adapting the opening in the wall to the entire frame structure of the present invention.

The compensating adjustments available at the thimbles 51 and 61 allow for obtaining counterbalancing action through the movements of both sashes under alternative I.

In view of the above, it will be seen that the several objects of the invention are achieved and other advantageous results attained.

75 As many changes could be made in the above

constructions without departing from the scope of the invention, it is intended that all matter contained in the above description or shown in the accompanying drawings shall be interpreted as illustrative and not in a limiting sense.

I claim:

A double-hung window comprising a frame having a sill, vertical grooved side jambs and a head jamb, a bumper on the head jamb, an upper outer sash and a lower inner sash slideable in the grooves in said side jambs, said lower sash having a vertical channel in the side thereof, an extension member secured to the top of the lower sash over the channel, said extension member having an aperture communicating with the channel, a bumper head extending upward from the extension member and located within the respective groove in the side jamb for cooperation with the bumper on the head jamb, cord guide means in the head jamb, and a cord at-

tached at one end to the upper sash, passing over said guide means and freely through said aperture, and attached at its other end to a weight freely movable in said channel, said weight having a portion wider than the aperture so that it cannot pass through said aperture.
